L. CHENOWETH

ICE CREEPER

Filed June 9, 1925

FIG. 2.

FIG. 3.

FIG. 4.

Inventor
Lloyd Chenoweth.

By

W. Murphy Jr.
Attorney

UNITED STATES PATENT OFFICE.

LLOYD CHENOWETH, OF COLDWATER, MICHIGAN.

ICE CREEPER.

Application filed June 9, 1925. Serial No. 35,941.

This invention relates to ice creepers, and has for one of its objects the provision of a novel, simple and highly efficient device of this character that may be readily secured 5 to a shoe against any movement with respect thereto and to attain this object the invention comprehends the employment of a spiked sole plate provided at its ends with the upstanding sole edge engaging loops, a toe strap connected to the loops, a heel strap connected to the loops, and an instep strap connected to the heel strap.

The invention is hereinafter fully described and claimed, and illustrated in the 15 accompanying drawing, wherein:

Figure 1 is a side elevation of a shoe equipped with an ice creeper constructed in accordance with my invention;

Figure 2 is a detail top plan view of the 20 ice creeper;

Figure 3 is a sectional view taken on the vertical plane indicated by the line 3—3 of Figure 2, and

Figure 4 is a detail perspective view of 25 the sole plate of the ice creeper.

Corresponding and like parts are referred to in the following description, and designated in the several views of the accompanying drawing, by similar reference characters.

30 The ice creeper comprises an elongated plate 1 of metal which is provided with downwardly extending spikes or prongs 2 and upwardly extending loops 3. The loops 3 are located at the ends of the plate 1 and are formed integrally therewith. They curve upwardly and inwardly, and are angularly related or converge in a forward direction.

40 The plate 1 is adapted to be applied to the bottom of the shoe sole in alignment with or slightly in advance of the widest part thereof, as illustrated in Figure 1. The shoe shown in this figure is of the waterproof type and embodies a rubber sole 4 and a rubber upper 5. The loops 3 curve inwardly 45 over the side edges of the sole 4 and have frictional engagement with said edges of the sole. Due to the engagement of the loops

3 with the side edges of the sole 4, due to the fact that the loops converge forwardly, and due to the point of application of the 50 plate 1 which positions the loops 3 at or slightly in advance of the widest portion of the sole, the plate cannot have any rearward movement with respect to the sole.

The plate 1 is held against downward 55 movement with respect to the sole 4 by an adjustable toe strap 6 which is engaged with the loops 3 and which also assists the loops 3 in holding the plate against rearward movement with respect to the sole. A heel strap 60 7 which is connected at one end to one of the loops 3 and at its other end to the tongue 8 of a buckle 9 which is carried by a tab 10 connected to the other loop, is adapted to prevent the plate 1 from having any forward 65 movement with respect to the sole 4. The heel strap 7 is supported in proper position on the shoe by an instep strap 11 which is connected at one end to a heel strap and at its other end to the tongue 8 of the buckle 9. 70

From the foregoing description, taken in connection with the accompanying drawing, it should be apparent that the ice creeper may be readily and quickly applied to a shoe, that it cannot become casually displaced, and that it is strong, durable and 75 efficient.

What is claimed is:

An ice creeper comprising a plate disposable against a sole in advance of the widest 80 portion thereof, said plate having its ends provided with upwardly and inwardly curved and forwardly converging loops, a toe strap connected to the loops, a heel strap connected to the loops, each loop having a 85 single opening with inner edges at a right angle to each other, the toe strap engaging corresponding edges of the openings, the heel strap engaging the other edges of the 90 openings, and an instep strap connected to the heel strap.

In testimony whereof I affix my signature.

LLOYD CHENOWETH.
